UNITED STATES PATENT OFFICE.

MARCELLIN CASTELNAU AND CHARLES THIALON, OF PARIS, FRANCE.

VAPOR-GENERATOR.

SPECIFICATION forming part of Letters Patent No. 696,797, dated April 1, 1902.

Application filed July 30, 1901. Serial No. 70,268. (No model.)

To all whom it may concern:

Be it known that we, MARCELLIN CASTELNAU and CHARLES THIALON, engineers, citizens of the Republic of France, residing at 43 5 Rue Violet, Paris, in the Republic of France, have invented certain new and useful Improvements in Vapor-Generators, of which the following is a specification.

Our invention relates to a generator of instantaneous vaporization capable of operating in a practical and durable manner at a very high pressure, such as that of eighty times the pressure of the atmosphere or even more.

15 The greater number of the generators of instantaneous vaporization made up to the present time comprise capillary passages, so that they become rapidly obstructed and are very difficult to clean.

20 We have found that calefaction and instantaneous vaporization can be produced without the help of capillarity, and we have endeavored to construct a vaporizing element having a large inner duct and no capillary 25 passages whatever.

To obtain elements capable of resisting high pressures and high temperatures, we had to give up laminated steel tubes, which expand and crack when subjected to a dull-red heat, 30 and when the passage of the water begins again after a longer or shorter interruption. We had also to give up tubes surrounded by a metal covering, for under the influence of irregular expansions the elements thus formed 35 become separated and can no longer be of use. We were thus brought to make ducts in blocks of steel sufficiently hard to withstand a higher temperature than that of a dull-red heat without losing a notable portion of their resistance.

40 However, as the vaporizing-ducts must of necessity present a somewhat extensive development a simple rectilinear duct in a block would be of no use, nor would it be advantageous either to make several rectilinear ducts 45 in the same block and to connect them together at their ends by curved connections, for there would be a great number of such connections, and that would be a source of inconvenience in many ways. In order that 50 each element or block of hard steel shall comprise a long inner duct without any connection, we arrange the said duct in zigzag or

spiral shape; but as it is impossible at present to make such a sinuous duct by mechanical means we have used a particular method 55 or process, consisting in so casting molten steel around a metal tube bent into spiral shape that the said tube shall become incorporated with the molten steel without leaving any other trace than that of the existence 60 of its inner and undisturbed duct. Our invention thus enables us to form elements in a single piece made of very resisting steel and provided with a long sinuous passage of a comparatively large diameter and by the 65 help of which elements we can constitute very high-pressure generators of instantaneous vaporization without any danger of such elements expanding or cracking or becoming obstructed or separated, as in the case of the 70 elements now in use, which operate, however, at a much lower pressure.

We show in the accompanying drawings a vaporizing element formed according to our invention, as well as a mold for manufacturing the same, and a generator comprising several of such elements.

Figure 1 shows an element in elevation, plan, and cross-section. Fig. 2 is a vertical section of a mold. Fig. 3 is a horizontal section on the line 3 3 of Fig. 2. Fig. 4 is a vertical section of a generator, and Fig. 5 is a horizontal section on the line J K of Fig. 4.

The element 9, Fig. 1, is a block of hard steel, in the interior of which is provided a 85 duct 10, bent back on itself three times over and of which the ends open out on one and the same surface. In order to obtain such an element, we arrange in a mold 1 a tube 8, made of steel and bent into the shape it is 90 desired to give to the duct, and so cast molten steel in the said mold that the said tube partially melts and becomes incorporated with the mass of steel without, however, being flattened or deformed in any other way. 95 Such a result can be obtained by causing the molten steel to flow through a certain number of casting-holes 2, suitably arranged according to the form and dimensions of the tube 8 and opening into the bottom of the 100 mold. The molten steel comes into all the parts of the mold at the same time and rises somewhat slowly therein, so that the tube 8 becomes surrounded by a quiet and almost

motionless liquid flux. The result is that the outer portions of the tube are melted and become incorporated with the molten steel, while the remainder of the tube is protected by a pasty sheath more consistent than the surrounding liquid. It will be understood, on the other hand, that if the liquid steel were allowed to circulate quickly along the said pasty sheath the latter would become dispersed, and the tube 8 would melt away entirely in a very short time.

Sections made in an element obtained by the above process show that there exists no joint in the mass and that there is no longer any trace of the tube save the inner part forming duct.

Another means which we intend to use concurrently with the one just described consists in filling the tube 8 previously with stearin or other suitable matter before arranging the same in the mold 1 in order that the said matter shall absorb a certain amount of heat and contribute to maintain the inner wall of the tube at a comparatively low temperature without, however, interfering with the melting down of the outer wall when brought into contact with the liquid steel.

Figs. 4 and 5 show a generator in which the elements 9 are arranged vertically in juxtaposition so as to form a cylindrical chamber containing the furnace. They are supported by an annular bottom 44, to which are fixed an ash-box 7 and two concentric partitions 45 and 46, forming a hollow casing, one part of which serves for the circulation of the gases of combustion. The latter rise at first into the chamber of the furnace 2, pass above the upper edge of the elements 9, move down into the space comprised between the latter and the partition 46, penetrate into an annular opening made at the base of the said partition, and pass into the atmosphere through a lateral chimney 8^a.

The elements 9 are connected together by curved tubes 21, connected in their turn to the pipes 11 and 12 (see Fig. 1) and located below the bottom 44. Only one tube 21 is

shown in Fig. 4 to make the drawing clearer. The feed-water is brought by a pipe 22, provided with a clack-valve 30, and circulates in a coiled heating-pipe 48, arranged around the elements 9. The water circulates afterward and successively in the elements 9, where it is vaporized by calefaction, and the vapor after having passed through the clack-valve 43 circulates in a coiled heating-pipe 49, arranged around the elements 9.

We claim—

1. A vapor-generator, comprising a cylinder built up of separate segmental blocks of steel fitted together so as to form a hollow cylinder, each block being provided with a duct and the several ducts communicating with each other, and means for heating the interior of said cylinder.

2. A vapor-generator, comprising a cylinder built up of segmental blocks of steel fitted together so as to form a hollow cylinder, each block being provided with a duct and the several ducts communicating with each other, means for heating the interior of said cylinder, and coils of pipe communicating with said ducts and surrounding said cylinder exteriorly.

3. As an article of manufacture, an element in the construction of generators, comprising a tubular member of steel having a general sinuous form and embedded in a stave-shaped block of cast-steel so as to be integral therewith.

4. As an article of manufacture, an element in the construction of generators, comprising a tubular member of steel making a plurality of return-bends upon itself and embedded in a solid block of cast-steel so as to be integral therewith.

In testimony that we claim the foregoing as our invention we have signed our names in presence of two subscribing witnesses.

MARCELLIN CASTELNAU.
CHARLES THIALON.
